UNITED STATES PATENT OFFICE.

JULIUS BING, OF EISENACH, GERMANY, ASSIGNOR TO THE FIRM MAGNET-WERK
G. M. B. H. EISENACH SPEZIALFAERIK FÜR ELEKTROMAGNET-APPARATE, OF
EISENACH, THURINGIA, GERMANY.

ELECTROMAGNETIC SEPARATOR.

Application filed November 10, 1924. Serial No. 749,059.

To all whom it may concern:

Be it known that I, JULIUS BING, a citizen of Germany, residing at Eisenach, in the State of Thuringia, Germany, have invented 5 certain new and useful Improvements in Electromagnetic Separators, of which the following is a specification.

This invention relates to electro-magnetic separators, and particularly to those in 10 which the introduction of the material into the magnetic field, and also the carrying of it out of the field, are effected with the aid of a drum, which surrounds a stationary magnetic system and rotates relatively 15 thereto.

The main object of the invention is to improve such separators in such a direction that they ensure an effective operation, are particularly adapted to separate even very 20 weakly magnetic material quite purely and rapidly, and at the same time are comparatively cheap to manufacture and to work.

With a view to attaining these as well as other aims, which will become evident incidentally to the more detailed description 25 hereinafter following of an embodiment of the invention, the invention consists essentially in such an arrangement of the separator that the magnetizable particles of 30 the material, while traversing the magnetic field, are repeatedly moved to and fro through the said field, so that their adhesion is loosened and the non-magnetizable particles entangled between the magnetizable 35 particles are set free. These non-magnetizable particles can then fall away unhindered during the traversing of the magnetic field.

A further characteristic of the invention consists in the fact that for attaining the 40 above-mentioned objects the drum jacket of the separator is constructed in such a way that it is divided in an axial direction into comparatively narrow strips of magnetizable and unmagnetizable material and at the 45 same time the magnet poles are so shaped and so arranged that the operative pole edges run obliquely to the direction of rotation of the drum, and the poles themselves engage with one another alternately in an 50 axial direction in such a way that the polarity of the parts of the jacket passing away over them is continually changing.

A further characteristic of the invention

consists in the special shaping and arrangements of the exciting winding for the magnetic system. 55

The invention is illustrated by way of example in the accompanying drawing, in which—

Figure 1 is a constructional form of the 60 new separator, the right-hand side of the figure being in elevation, the left-hand side in axial sectional elevation and the middle showing a side elevation of the magnet body with the drum jacket removed. 65

Figure 2 is a section on the line 11—11 in Figure 1.

Figure 3 shows the exciting windings in perspective.

The separator consists essentially of the 70 stationary magnetic system 1, and of the drum 2 enclosing this system. The magnet system 1 surrounds the shaft 3, which rests at its ends in bearings 4, 4 and is hindered upon its rotating by the holder 5. The 75 middle thickened part of the shaft 3 carries, in the constructional form illustrated, three magnet bodies 6 keyed firmly to the shaft. Of these magnet bodies the two outer ones, 6^a and 6^b are unilateral, while the middle 80 one 6^c is substantially symmetrically constructed. The two outer or lateral magnet bodies 6^a and 6^b each comprise a hub part, 7^a and 7^b respectively, a sector or disc-shaped part, 8^a and 8^b respectively, projecting therefrom radially, and a pole part 10^a and 10^b respectively consisting of a plurality of inwardly directed pointed teeth or projections, 9^a and 9^b respectively, and having a co-axial cylindrical outer surface. In the 85 case of the middle magnet body 6^c the disc part 8^c is fitted in the middle to the hub body and the pole part 10^c, the outside of which likewise lies in the above mentioned cylindrical surface, is symmetrically constructed in so far as the pointed teeth 9^c project towards both sides of the central plane 90 in an axial direction. There is however a lack of complete symmetry, in so far as the teeth on the one side do not lie exactly opposite to the teeth on the other side, the teeth on the two sides being arranged in 95 staggered relationship to one another. The teeth 9^a and 9^b of the outer pole body are also staggered relatively to the teeth 9^c of 100 the central pole body 6^c, in such a way as 105

to engage in the intervening spaces formed by the teeth 9^c, while conversely the teeth 9^c engage in the intervening spaces between the teeth 9^a and between the teeth 9^b of the 5 lateral magnet bodies 6^a and 6^b respectively. Between the substantially parallel edges of the opposing teeth are left certain distances, which are designated 11 in Figure 1. The disc parts 8, as well as the pole parts 10 of 10 the magnet bodies 6, in a known manner, as shown in Figure 2, do not extend throughout the entire periphery, but only form sectors which, as the dotted lines indicate, extend round at both ends somewhat beyond 15 the axial central plane in question. The three magnet bodies 6^a, 6^b and 6^c form together two separate magnetic systems, which have however a common exciting coil 12.

This exciting coil is made by winding the 20 requisite number of turns of wire into a longitudinal closed loop, the individual turns lying in substantially parallel planes, and by then bending the arcuate end parts of these loops back through a right angle, thus 25 producing the formation illustrated in Figure 3, which is then slid with the arcuate parts over the hub parts 7 of the magnet bodies, while the straight parts 13 connecting them come to lie along the shaft 3 and 30 the radial rear sides of the segments 8. The exciting current is supplied to the winding 12 by means of a lead 16 passing through holes 15 bored in the shaft 3 and in the magnet bodies.

35 The exciting of the two separate magnetic systems may of course alternatively be effected in the otherwise usual manner with the aid of two annular coils. The construction described offers however substantial advantages. In the first place it requires less copper than two separate windings. Above all, it obviates the excessive and harmful leakage which occurs in the case of annular windings on the rear side of the magnet 40 sectors 8 and which causes the magnetic field to extend in reality in rather considerable strength out beyond the ends of the sectors in a peripheral direction and causes the magnetic constituents of the material to be carried along beyond the actual boundaries of 45 the separation zone, which of course impairs the satisfactory working of the separator. This disadvantage makes itself felt particularly in the case of separators the drums of 50 which are provided with coverings consisting of magnetizable material, as will herein-after be described.

The hereinbefore described construction of 55 the magnet bodies enables the separator to be conveniently assembled and taken to pieces. Also types of separators of greater length easily admit of being manufactured by the aid of magnet bodies of the construction described. If it is desired to build a 60 separator of greater length and at the same

time of greater capacity, all that is necessary is to fit one or more additional magnet bodies, of the same nature as the central body 6^c illustrated in Figure 1, on to a correspondingly prolonged shaft. When employing 70 exciting windings of the form illustrated in Figure 3, two further magnet bodies like 6^c for each additional winding must then always be added.

The drum 2 containing the two magnetic 75 systems comprises essentially the two end shields 17 and 18, which are rotatably supported on the parts of the shaft 3 located between the magnet bodies 6^a and 6^b and the bearings 4, 4. The two shields 17, 18 are 80 connected with one another by a cylindrical jacket 19, which is mounted at its ends on inwardly directed flange-like projections 20 on the shields 17 and 18. The jacket may consist of non-magnetizable material, such 85 as brass, or of magnetizable material. In the latter case either the thickness of the jacket is kept very small, so that it takes up no appreciable number of lines of force, or else a sheet material of very low magnetic 90 conductivity or permeance is used, such as manganese steel.

The jacket 19 is provided with a covering 95 which is divided stripwise into magnetizable and non-magnetizable material. The covering may be made for example by winding wires of quadrilateral cross section side by side on the jacket 19 into the form of a flat-threaded screw. This is done preferably 100 with wires in pairs, one quadrilateral wire, such as 21, consisting of magnetizable material, iron for example, and the adjacent quadrilateral wire, such as 22, of non-magnetizable material, for instance brass. The adjacent turns of the winding are preferably 105 soldered or welded on one another and also to the drum jacket 18, and then turned up smooth on the outside.

The right-hand drum end shield 18 is provided with a toothed ring 23, which gears 110 with a toothed wheel not shown, by means of which the drum is set in rotation.

In operating the separator, the material, preferably finely divided, is supplied in a known manner by means of a feed channel 115 on the upper side of the drum 2. It then travels with the drum in the direction of the arrow in Figure 2 through the magnetic field. The magnetizable particles of the material are in that case particularly strongly attracted at the outer edges of the strips 21 of magnetizable material, where the lines of force concentrate. Here rows of clusters 120 of magnetic particles form, which however, while travelling through the magnetic field continually change their direction, since the strength of the fields of force traversed in the travelling, as well as their polarity are also incessantly changing, the inductive effect of the magnet poles on the magnetizable 125 material.

strips of the drum-jacket covering changing both with the dimensions and with the position and boundaries of the parts of the magnet poles that are for the time being covered. 5 This phenomenon has the result that the magnetic particles adhering to the edges of the strips 21 are to a certain extent shaken to and fro and loosened, so that the non-magnetizable particles enclosed by them have 10 an ample opportunity, during the traversing of the magnetic field, to become free and drop out. In this manner a very clean and effective separation of the material is obtained even when treating very feebly magnetic material. 15

When the drum, with the material located upon it, has travelled past the magnet sector, the material arrives, in so far as it still adheres to the drum in the non-magnetic zone. Since here, on account of the special construction of the magnet winding, the leakage line formation is exceedingly small, even the iron strips 21 of the drum covering cannot concentrate in themselves any considerable number of lines of force, so that they remain practically, unmagnetic and soon after passing the lower vertex of the drum even the magnetizable particles drop off. 20

30 I claim:—

1. Electro-magnetic separator comprising: a magnet system; a drum enclosing said magnet system and rotatable relatively to it; the magnet poles of said system lying substantially in a cylindrical surface coaxial to said drum and having edges lying obliquely to the generatrix of said cylindrical surface; said drum comprising substantially helically arranged strips consisting alternately of magnetizable and non-magnetizable material. 40

2. Electro-magnetic separator comprising: a magnet system; a drum enclosing said magnet system and rotatable relatively to it; the magnet poles of said system lying substantially in a cylindrical surface coaxial to said drum and having edges lying obliquely to the generatrix of said cylindrical surface; an iron wire winding and a brass wire winding on said drum; each turn of said iron wire winding alternating with a turn of the brass wire winding; adjacent turns of said windings intimately connected to one another and to the drum. 50

55 3. Electro-magnetic separator comprising: a magnet system; a drum enclosing said magnet system and rotatable relatively to it; the magnet poles of said system lying substantially in a cylindrical surface coaxial to said drum and having edges lying obliquely to the generatrix of said cylindrical surface; an iron wire winding and a brass wire winding on said drum; each turn of the iron wire winding alternating with a turn of the brass wire winding; adjacent

turns of said windings soldered to one another and to said drum; said windings being turned up smooth on the outside. 60

4. Electro-magnetic separator comprising: a magnet system having magnet poles; a drum enclosing said system and rotatable relatively to it; the outside surfaces of said magnet poles lying substantially in cylindrical surfaces parallel to the drum surface and having edges extending obliquely to the 75 generatrix of said cylindrical surfaces; said drum comprising circumferentially extending strips of alternately magnetic and non-magnetic material. 80

5. Electro-magnetic separator comprising: a magnet system having magnet poles; a drum enclosing said system and rotatable relatively to it; the outside surfaces of said magnet poles lying substantially in cylindrical surfaces parallel to the drum surface and having edges extending obliquely to the 85 generatrix of said cylindrical surfaces; a winding of magnetizable quadrilateral wire secured to the outside of said drum; a second winding of non-magnetizable quadrilateral wire secured to the outside of said drum; each turn of the one winding adjacent to a turn of the other winding; the adjacent turns intimately connected to one another and to the drum. 90

6. Electro-magnetic separator comprising: a magnet system; a drum enclosing said system and rotatable relatively to it; the poles of said system being formed of axially projecting tooth like parts having 100 oblique edges lying substantially in a cylindrical surface coaxial to said drum; two quadrilateral wires, one of magnetizable the other one of non-magnetizable material; said wires wound with pairs in the form of 105 a flat-threaded screw onto said drum; the single turns of said windings soldered to one another and to said drum, and turned up on the outside. 110

7. Electro-magnetic separator comprising: a magnet system; a drum enclosing said system and rotatable relatively to it; the outer surfaces of said magnet poles lying substantially in cylindrical surfaces parallel to the surface of said drum and having edges extending obliquely to generatrixes of said cylindrical surfaces; said drum having a covering consisting substantially of circumferentially extending strips 115 of alternately magnetizable and non-magnetizable material. 120

8. Electro-magnetic separator comprising: a magnet system having poles of different polarity; a drum enclosing said magnet system and rotatable relatively to it; the poles of different polarity forming two opposite groups of pointed teeth axially projecting in different directions; the pole teeth of the one group projecting into the 125 interstices formed by the teeth of the other 130

group; two quadrilateral wires, one of magnetizable the other one of non-magnetizable material; said wires wound in pairs in the form of a flat-threaded screw onto said

5 drum and rigidly secured to it.

9. Electro-magnetic separator comprising: a magnet system; a drum enclosing said magnet system and rotatable relatively to it; pole pieces of different polarity arranged on said magnet system in such a way as to form between them gaps of zig-zag-like configuration; said drum containing substantially circumferentially elongated parts consisting alternately of magnetizable and non-magnetizable material.

10. Electro-magnetic separator comprising: a magnet system having poles of different polarity; a drum enclosing said magnet system and rotatable relatively to it; 20 the poles of different polarity forming two opposite groups of pointed teeth axially projecting in different directions; the pole teeth of the one group projecting into the interstices formed by the teeth of the other 25 group; said drum having substantially helically arranged metal strips consisting in the axial direction alternately of magnetizable and non-magnetizable material.

11. Electro-magnetic separator comprising: a magnet system having poles of different polarity; a drum inclosing said magnet system and rotatable relatively to it; the poles of different polarity forming two opposite groups of pointed teeth axially 30 projecting in different directions; the pole teeth of the one group projecting into the interstices formed by the teeth of the other group; said drum comprising a sheet metal jacket and a series of strips of quadrilateral section secured adjacently to each other to 35 said jacket and extending substantially in a circumferential direction; said strips consisting alternately of magnetizable and non-magnetizable material.

40 12. Electro-magnetic separator comprising: a magnet system; a drum enclosing said magnet system and rotatable relatively to it; the magnet poles of said system lying in a cylindrical surface coaxial to said 45 drum and having edges lying obliquely to the generatrix of said cylindrical surface; said drum having a covering of alternately magnetizable and non-magnetizable strips lying adjacent one to another; pole pieces 50 on said magnet system; the operative edges of said pole pieces and of said strips substantially crossing each other.

55 13. Electro-magnetic separator comprising: a magnet system; a drum enclosing said magnet system and rotatable relatively to it; the magnet poles of said system lying in a cylindrical surface coaxial to said drum and having edges lying obliquely to the generatrix of said cylindrical surface; 60 said drum comprising a jacket of thin sheet

metal; a plurality of strips of alternately magnetizable and non-magnetizable material and extending substantially circumferentially secured to said jacket.

65 14. Electro-magnetic separator comprising: a stationary magnet system; a rotatable drum enclosing said magnet system and having a jacket of sheet metal; two windings of quadrilateral wire on said jacket, one of said windings of iron and the other one of brass; said windings being so arranged that each turn of the one winding will alternate with a turn of the other winding; each turn soldered to the adjacent turn and to the sheet metal jacket; said magnet system having pole pieces lying in a cylindrical surface substantially coaxial to said drum, and having edges extending obliquely to the generatrix of said cylindrical surface.

70 15. Electro-magnetic separator comprising: a stationary magnet system; a rotatable drum enclosing said magnet system and having a jacket of thin sheet metal; two windings of quadrilateral wire on said jacket, one of said windings of iron and the other one of brass; said windings being so arranged that each turn of the one winding will alternate with a turn of the other winding; each turn soldered to the adjacent turn and to the sheet metal jacket; said magnet system having pole pieces the outer surfaces of which lying in a cylindrical surface substantially coaxial to said drum; said pole pieces having axially projecting pointed teeth reciprocally engaging each other.

75 16. Electro-magnetic separator comprising: a stationary magnet system; a rotatable drum enclosing said magnet system and having a jacket of thin sheet metal; two windings of quadrilateral wire on said jacket, one of said windings of iron and the other one of brass; said windings being so arranged that each turn of the one winding will alternate with a turn of the other winding; each turn soldered to the adjacent turn and to the sheet metal jacket; said pole pieces forming two opposite groups of teeth axially projecting in different directions; the pole teeth of the one group projecting into the interstices formed by the pole teeth of the other group.

80 17. Electro-magnetic separator comprising: a magnet system; a drum enclosing said system and rotatable relatively to it; the edges of the poles of said magnet system adjacent to said drum lying substantially in a cylindrical surface coaxial to said drum and extending obliquely to the axis of the drum; said drum comprising substantially circumferentially extending strips of alternately magnetizable and non-magnetizable material.

85 18. Electro-magnetic separator comprising:

ing: two magnet bodies; a drum enclosing said magnet bodies and rotatable relatively to them; said drum having a covering consisting of substantially circumferentially extending strips of alternately magnetizable and non-magnetizable material; and a single exciting coil common to said two magnet bodies.

19. Electro-magnetic separator comprising: two magnet bodies; a drum enclosing said magnet bodies and rotatable relatively to them; two quadrilateral wires, one of magnetizable the other one of non-magnetizable material, and wound one adjacent to the other in the form of flat-threaded screw turns onto said drum and rigidly secured to it, and a single exciting coil common to said two magnet bodies.

20. In an electro-magnetic separator two magnet bodies; at least one of said magnet bodies comprising two pole shoes, two sector-like core pieces and a hub-like yoke piece; a single exciting coil common to said two magnet bodies and only partly surrounding the yoke pieces of the magnet bodies; a drum enclosing said magnet bodies and rotatable relatively to them; said drum having a covering consisting of substantially circumferentially disposed strips of alternately magnetizable and non-magnetizable material.

21. In an electro-magnetic separator two magnet bodies; at least one of said magnet bodies comprising two pole shoes, two sector-like core pieces and a hub-like yoke piece; a single exciting coil common to said two magnet bodies and only partly surrounding the yoke pieces of the magnet bodies; a drum enclosing said magnet bodies and rotatable relatively to them; two quadrilateral wires,

one of magnetizable the other one of non-magnetizable material; said wires wound onto said drum in the form of flat-threaded screw turns; the single turns of said wires soldered to each and to said drum, and turned up smooth on the outside.

22. Electro-magnetic separator comprising: two magnet bodies; a drum enclosing said magnet bodies and rotatable relatively to them; the outer surfaces of the pole pieces of said magnet bodies lying substantially in a cylindrical surface coaxially to said drum, and having edges extending obliquely to the generatrix of said cylindrical surface; said drum comprising strips of magnetizable and non-magnetizable material disposed alternately adjacent each other in the axial direction; and a single exciting coil common to said two magnet bodies.

23. Electro-magnetic separator comprising: two pole bodies each having pole pieces; a drum enclosing said pole bodies and rotatable relatively to them; said drum having a covering consisting of strips of magnetizable and non-magnetizable material, alternately disposed adjacent to each other on said drum and extending substantially in the form of flat-threaded screw turns around said drum; the operative edges of said pole pieces crossing said strips in acute angles; and a single exciting coil common to said two magnet bodies.

In testimony whereof I affix my signature in presence of two witnesses.

JULIUS BING.
